UNITED STATES PATENT OFFICE.

OMER L. ROBERTS, OF MACY, INDIANA.

INSULATOR.

1,305,168.

Specification of Letters Patent. Patented May 27, 1919.

Application filed July 21, 1918, Serial No. 110,539. Renewed March 7, 1919. Serial No. 281,293.

To all whom it may concern:

Be it known that I, OMER L. ROBERTS, a citizen of the United States, residing in Macy, county of Miami, State of Indiana, 5 have invented certain new and useful Improvements in Insulators, of which the following is a specification.

My invention relates to improvements in electric insulating devices and more particularly to devices of this character which are utilized to support telegraph, telephone, electric light and other electric current conducting wires from posts or other suitable supports. 10 Heretofore wires used for this purpose have generally been supported from top caps of glass or similar non-conducting material, attaching the wires to the caps by separate binding wires or by winding the wires 15 around the cap. This construction while apparently the best devised for this purpose prior to my present improvement has some disadvantages in that the binding wires may divert the electric current and in some instances cause short circuiting, the wiring is somewhat difficult and slow to put up and requires the services of skilled electricians and when erected under certain conditions is apt to allow excessive vibration, creating 20 buzzing or ringing sounds that in the case of telegraph and telephone wires would materially interfere with the clearness of the sending and receiving.

The objects of my invention are to secure 25 perfect insulation under all conditions, to eliminate the use of separate binding wires, to avoid bending or curving the conducting wires about the insulators, to so construct the insulating devices that the conducting wires 30 may be placed in position upon a post or detached therefrom very rapidly and effectively without the aid of pliers or other tools and by ordinary workmen, to prevent the collection of moisture upon or near the conducting wires apt to cause short circuiting, to support the conducting wires in an approximately straight line and to render the voice or other sounds carried over the wires, plainer, more distinct and louder. 35 These and other advantages I accomplish by my improved device as hereinafter set forth in the following description and as more particularly pointed out in the appended claims, reference being had to the 40 accompanying drawings in which an em-

bodiment or adaptation of my invention is shown.

In the drawings—

Figure 1 represents a side elevation of one embodiment of my improved insulating device. 60

Fig. 2 is a central longitudinal section through the embodiment of my improved insulating device shown in Fig. 1, taken on line 2—2 in said Fig. 1, the arm or branch 65 upon which the insulation proper is mounted being shown in side elevation.

Fig. 3 is an enlarged section through the insulator base taken on line 3—3 Fig. 4.

Fig. 4 is an enlarged, detached top or plan view of the insulator base, showing the groove in which the electric conducting wire is supported. 70

In referring to the embodiment or adaptation of my improved insulating device 75 shown in the accompanying drawings in detail, like numerals indicate corresponding parts.

The embodiment or adaptation of my improved insulating device as illustrated is 80 principally adapted to be attached to or supported from a pole or similar suitable article.

It comprises, in brief, a suitable supporting arm or branch, a base which preferably is of a ring-like form and a top cap. 85

The arm or branch, 1, is preferably constructed of wood or other suitable material and has its upper portion reduced in size and to a circular form, being screw-threaded as shown at 2, in Fig. 2. This arm is provided with apertures 3, through which screws or other fasteners may be inserted to secure the arm to a post or other suitable support. 90

The base, 4, is fitted upon the upper portion of the arm or branch 1, being slipped over the same and around a tapering medial portion, 5, of said arm as shown in Fig. 2. This base is constructed of glass, porcelain, earthenware or other suitable insulating material and it is provided on its top surface with a straight groove, 6, of sufficient depth to receive an electric conducting wire, 7, as shown in Fig. 2. This groove it will be noted from Fig. 4 extends on one side of 95 the central opening, 8, through the base. The base is also provided on its inner, annular wall surrounding the central opening, 8, with a series of longitudinal grooves, 9, which constitute passage ways for water or 100

110

moisture. These transverse grooves, 9, as shown in Fig. 3 gradually deepen and widen from the top of the base downward to the bottom surface thereof, thus permitting the 5 water or moisture that collects upon the top surface of the base or within its center opening to freely flow downward and out of the same.

Preferably the top groove in the base is 10 made deep and wide enough to form a snug fit for the conducting wire placed therein.

The conducting wire is locked or secured in the top groove, 6, by a screw cap, 10, which is preferably formed as shown in 15 Figs. 1 and 2 being provided with an internal screw-thread into which the screw-threaded upper portion, 2, of the arm, 1, engages an exterior groove, 11, which extends horizontally and circumferentially 20 around an intermediate portion thereof. The groove, 11, may be employed to secure a conducting wire to the support in the old and well known way if desired.

In putting up wires with my improved 25 insulating device, the arm or branch, 1, is suitably attached to a pole or other support, the base is slipped over the upper end of the arm and upon the medial portion of the same, the conducting wire is fitted in the top 30 groove, 6, being flush with a top surface of the base and the top cap is screwed down upon the base, thereby firmly holding and locking the conducting wire in the groove. The top cap like the base can be constructed 35 of glass, porcelain, earthenware or any other suitable insulating material.

The principal advantages of my improved insulating device are that the insulation and the conducting wires can be assembled or 40 dismounted much more quickly and more effectively than by the present devices now universally in use, that the conducting wires are supported in a tight condition, are perfectly insulated, are not liable to short circuiting and do not require separate binding 45 wires. Other advantages are that the wires can be put up much more rapidly and by ordinary workmen, thus rendering it decidedly cheaper to use my improved device.

My improved device also practically eliminates vibration and buzzing sounds and makes the sounds and voices carried over the wires more audible, plainer, louder, clearer and much more distinct.

While I have herein described a certain 55 embodiment or adaptation of my improved insulating device it is to be understood that it may be varied or changed within the scope of the following claims without departing from the spirit of my invention.

Having thus described my invention, what I claim to be new and patentable is:

1. In an insulating device for supporting electric conducting wires, a suitable supporting arm having a screw-threaded upper portion and a tapering medial portion, a ring like base of insulating material slipped over the screw-threaded portion and fitted upon the tapering medial portion said base having a top groove adapted to receive and support an electric conducting wire, and a series of interior grooves forming passage ways for the flow of moisture, and a top cap of insulating material adapted to screw upon the screw-threaded upper portion of 70 the arm and against the base to fasten the conducting wire in the groove.

2. In an insulating device for supporting electric conducting wires, a suitable supporting arm having a screw-threaded upper portion and a tapering medial portion, a ring like base of insulating material slipped over the screw-threaded portion and fitted upon the tapering medial portion said base having a horizontal top groove adapted to receive and support an electric conducting wire, and a series of vertically extending interior grooves forming passage ways for the flow of moisture, and a top cap of insulating material adapted to screw upon the screw-threaded upper portion of the arm and against the base to fasten the conducting wire in the groove.

OMER L. ROBERTS.
